ROLLING DIRT MOVER

Charles Le Bleu, Los Angeles, Calif.

Application February 19, 1934, Serial No. 711,953

16 Claims. (Cl. 37—140)

This invention relates to a material moving machine to be moved over the surface of the ground and operable to scrape up material therefrom, to transport a collected load, of material 5 and to discharge or unload the transported load, each of the operations being under the control of the machine operator. Machines heretofore used for such purposes in respect to the transporting of the load may be placed in the following two 10 classes: those which have ground wheels; and those having no ground wheels or equivalent supporting means. Those having wheels either carry the entire load of material or a part thereof on the wheels.

15 Those without wheels drag the entire load over the ground. The dirt is commonly collected and transported in a container known as a bucket or scoop and these scrapers without wheels drag the bucket or scoop over the ground to transport the 20 load from one place to another. Wheeled scrapers which do not support the entire load act partially as a drag scraper.

Those machines having wheels to carry the load require a frame structure which must be 25 strong enough to suspend the bucket or scoop with its charge of material. In large capacity machines, four wheels are commonly used. In smaller capacity machines, two wheels commonly disposed at the sides or rear are used and the 30 front of the frame is supported on the rear of a tractor.

Obviously since the load in the type of scraper having no wheels is not supported by the frame but by the material container itself, the frame 35 structure may be much lighter in weight than that of a wheeled scraper. It follows that the expense of and attention to wheels, bearings and associated parts is saved. However, the drag scraper is not as easily drawn as that having 40 wheels or rolling supports.

It is the primary object of this invention to provide a material or dirt moving machine including a container acting as a drag scoop or bucket during loading and as a roller during 45 transportation of the load. It is another object of this invention to provide a structure of the character described having a drum like container and a shutter arranged to open and close a peripheral opening therein and when closed to 50 form a complete substantially cylindrical surface mounted to be revolved and serve as a ground roller carrying the load.

A further object of this invention is to provide 55 a machine of the character described wherein power is transmitted to the shutter from the draft

or traction device to open or close the latter. A still further object of this invention is to provide a machine of the character described wherein the material receiving edge of the container may be adjusted in relation to the surface 60 over which the container is drawn and such adjustment obtained by power transmitted from the draft or traction device.

These objects together with other objects and accomplishments pertaining to details of structure are obtained by the embodiments of my invention illustrated in the accompanying drawings, in which:

Figs. 1 to 7 inclusive illustrate one embodiment of my invention: Fig. 1 is a side elevational view 70 of a material mover with parts in skidding position; Fig. 2 is a plan view of the structure shown in Fig. 1, substantially one half of the structure being shown, the other half being duplicated; Figs. 3, 4 and 5 are side elevational views on an 75 enlarged scale showing parts in digging, transporting and dumping positions respectively; Fig. 6 is a fragmentary side elevational view of the structure with parts in initial position to close the shutter; Fig. 7 is an enlarged sectional view 80 of the catch mechanism for the shutter as seen on a plane extending longitudinally therethrough; Figs. 1—A, 3—A, 4—A and 5—A are plan views of the latching mechanism for the container in positions corresponding to those of 85 Figs. 1, 3, 4 and 5; Figs. 8 to 15 inclusive illustrate another embodiment: Fig. 8 is a side elevational view of another embodiment of my invention; Fig. 9 is a plan view of a fragment of the structure shown in Fig. 8; Fig. 10 is an enlarged sectional view of a swivel tube connection taken through a trunnion; Figs. 11, 12 and 90 13 are elevational views of the structure shown in Fig. 8 with parts in digging, transporting and dumping positions respectively; Fig. 14 is a transverse sectional view through the hydraulic motor for adjusting the relative positions of the shutter and container; and Fig. 15 is a sectional view as seen on the plane indicated by 15—15 in Fig. 14.

Referring more particularly to the drawings 106 and the embodiment of the invention shown in Figs. 1 to 7 inclusive, a frame is shown comprising side bars 20, a rear bar 21, front bar 22 and draw bar 23. This frame may be in general of a conventional type and made up of structural steel bars of suitable shapes, welded, riveted or otherwise secured together. As the structure of the scraper is duplicated on opposite sides, only one half is shown in Fig. 2 and only one half of the duplicate structure is described. A fragment of 105 110

- a tractor for drawing the scraper is indicated by T. Secured to the side bars 20 are bearing blocks 24 in which trunnions on the bowl or container 25 are journaled.
- 5 The bowl or container 25 comprises a sectional cylindrical shell 26 with an axially extending opening 27. End plates 28 of circular form are secured to shell 26. At one margin of the opening is a digging or material receiving plate 29.
- 10 As is common in bowls which are rolled to obtain various positions of the material receiving edges, shoes 30 are provided peripherally spanning the opening 27. These shoes may be bolted or otherwise secured to end plates 28. Trunnions 31 are fastened to the end plates 28 and are journaled in bearing blocks 24 so that the bowl or container 25 may be revolved.
- 15 A shutter 32 for the container 25 comprises a sectional cylindrical wall 33 and sectoral end plates 34 with a central circular portion partially bounded by an outstanding rail 35. This rail may be a channel bar secured to end plates 34. Rail 35 has a gap 35a. Shutter 32 is journaled on trunnions 31 so that it may be revolved with respect to the container 25. The shutter overhangs the container and may be positioned to cover the container opening or to open the latter. As later described, the shutter 32 may be coupled to the container in closed position so that the 20 container and shutter as a unit form a closed revolvable drum which acts as a ground roller. The shutter may be held against revolution and the container may be held adjustably against revolution to obtain various positions of its receiving edge.
- 25 The container has peripherally and radially spaced keeper blocks 36 and 37 secured to end plates 28. Block 37 is stepped on its surface as indicated by 37a and 37b. Mounted on the side bars 20 are latches for engagement by the keeper blocks. Each latch comprises an arm 38 having a pintle 39 secured thereto intermediate its ends. The pintle is journaled in a bearing block secured to side bar 20 with arm 38 below the bar.
- 30 Secured to the pintle 39 above bar 20 is a crank arm 40. A link 41 is pivotally secured to the outer end of crank arm 40. The other end of link 41 is pivotally secured by a pin 42 to a link 43. The other end of link 43 is pivotally secured to the bearing block on the bar 20. Pin 42 has a ball head nested within a socket 44 on the end of an actuating rod 45. By moving rod 45 longitudinally, motion will be transmitted to arm 38 causing the latter to be turned. The particular 35 mechanical motion between rod 45 and arm 38 is not pertinent to the inventive feature, and has been selected in order to produce a comparatively large throw of arm 38 with a short movement of rod 45. Other movements as found mechanically expedient may be employed. The arm 38 may be positioned by means of rod 45 so as to be engageable by either step 37a or 37b of block 37 or by block 36 or to clear both blocks. Control means for moving rod 45 is provided and 40 comprises a rocker having arms 46 pivotally secured to side bars 20. A yoke bar 47 of T form is shown connecting arms 46 so that the arms 46 and bar 47 form a unitary rocker referred to hereafter as rocker 46. Rods 45 are secured by ball and socket joints 48, one to each arm 46. Thus, when the rocker is moved, the rods 45 will be moved therewith and cause latch arm 38 to be turned. Pivotally secured to yoke bar 47 is a link 49. Mounted on draw bar 23 is a pair of spaced bearing plates 50 between which a lever 45
- bar 51 is pivotally mounted. The bar 51 is pivotally mounted intermediate its ends and one arm thereof is pivotally secured to link 49. The structure is such that by rocking lever 51 forwardly, the rocker 46 will be swung backwardly and vice versa. A pull rope 52 shown in Fig. 1 is intended to be secured to the other arm of lever 51 and the latter can only be rocked forwardly by means of the rope. To move the rocker 46 forwardly, a lever 53 comprising two bars is pivotally secured at one end to a bearing plate 54 mounted on draw bar 23. A pin 55 extends between the bars of lever 53, and extending between the bars with pin 55 in an elongated slot 56 is a connecting link 57 which is pivotally secured at the other end to yoke bar 47. A pull rope 58 shown in Fig. 1 is secured to lever 53. A forward pull on rope 58 swings lever 53 forwardly and link 57 in the same direction. This causes rocker 46 to be swung forwardly. Obviously neglecting the play allowed pin 55 by slot 56, movement of either lever 57 or 51 causes reverse movement of the other.
- 50 When the container 25 is in skidding position as shown in Figs. 1 and 2, the latch mechanism 100 for the container is in the position shown in Fig. 1-A. Arm 38 will be disposed so that one end will register with keeper block 37 and the high step 37a thereof. Thus, when the scraper is drawn along the ground, step 37a engages arm 105 38 and revolution of the container is arrested with the material receiving edge 29 in skidding position. The shutter 32 is maintained in open position by mechanism later described. To attain digging position, lever 53 is pulled forward a slight 110 distance, swinging rocker 46 forward and arm 38 with an end registering with step 37b as shown in Fig. 3-A. This allows the container to revolve until arrested by step 37b engaging arm 38 so as to dispose the material receiving edge 29 in 115 digging position as shown in Fig. 3. The next event is transporting of the load. The shutter 32 is caused to be moved to closed position over the container 25 and coupled thereto so as to be revolved with the latter. The arm 53 is swung 120 further forward to the position shown in Fig. 4. This places the latch mechanism elements in the position shown in Fig. 4-A, the arm 38 being out of line with both blocks 36 and 37 so that the 125 container 25 and shutter 32 may be revolved as a drum and serve as a ground wheel. The material gathered in the container will be held therein and transported. The next event is dumping of the load. The shutter 32 is arrested in the position 130 shown in Fig. 5. The lever 53 is swung further forward to the position shown in Fig. 5 so as to position an end of the arm 38 in the path of block 36 and the latter may engage the arm 38. This arrests the container 25 with the material 135 receiving edge 29 in position such that with shutter 32 open, the load will be dumped. The cycle of events is then repeated by first pulling arm 51 forward to a position returning the latch mechanism parts to the positions shown in Fig. 1-A. 140 The shutter 32 is caused to be positioned as shown in Fig. 1 and the container to be arrested in skidding position.
- 145 The shutter catch mechanism comprises an abutment plate 59 pivoted at 60 to the frame. It has abutment projections 61 and 62 spaced from one another. On the shutter is a lift latch 63, best shown in Fig. 7. It is pivoted at 64 to the shutter end wall 34 so as to have two arms. On one of the arms is a stop projection 65 arranged 150

to be selectively engaged either with abutment 61 or 62 or to clear the abutments. A compression spring 66 disposed in a socket of the latch 63 seats against the end plate 34 and tends to maintain a hook end 67 inwardly toward the end plate 28 of container 25. The lift latch 63 riding against abutment 61 or 62 will move the latch 63 so that it is in its outer position with projection 65 engaged with the abutments. Thus, the shutter may be held in the positions shown in Figs. 1, 3 and 5 or released for revolution as shown in Fig. 4. Positioning of the plate 59 may be obtained from rocker 46 so as to be coaxially positioned with the latch mechanism for the container. To this end, a connecting link 68 is pivotally secured to plate 59 and is slidably passed through the leg of yoke bar 47. A nut 69 is secured to the outer end of link 68 and a slideable washer 70 is mounted on the other side of the leg. A compression spring 71 seats at one end against washer 70 and at the other end against plate 59 so as to form a compressively resilient link. An arm 72 fixed to plate 59 serves for independent operation of the latch mechanism. The parts of the latch mechanism are so related to the parts of the catch mechanism that when the container 25 is in skidding position as shown in Fig. 1, abutment 61 will be engaged by projection 65 on latch 63 and the shutter held open. It will be noted that the engaging surface of abutment 61 is long enough to allow plate 59 to be rocked to the digging position without disengaging projection 65. Thus, in operation of the control mechanism arm 38 may be passed from skidding to digging positions and shutter 32 maintained open. It will be noted that in skidding position the pivotal axes of link 49 and pin 55 are in line so as to lock the control mechanism in this position from displacement by any thrust transferred from the container or shutter. Slot 56 allows the arm 53 to drop back in digging position with the axes and pin in line to maintain this lock relation. The position of parts in the transporting event shown in Fig. 4 is such that the abutments 61 and 62 are disposed on the outer and inner sides of the line of travel of latch 63 releasing the shutter 32 and may ride on the sides of rail 35.

In manipulating the mechanism to obtain transporting position, arm 72 is first pulled forward to release shutter 32 which drops by its own weight to engagement with the ground and the arm 72 is then released. Compression spring 71 permits this movement without disturbing rocker 46. Upon release of arm 72, rail 35 prevents return of plate 59 to arresting position by reason of block 61 riding on rail 35. The position of the latch mechanism parts is that shown in Fig. 3-A. On the end wall 28 of container 25 is a keeper block 73 having a bevelled face for hook 67 to ride over and an engagement face 74 for the hook. Upon release of the shutter 32, it drops to engage the ground and hook 67 rides over block 73 to face 74 so that revolution of container 25 would carry along shutter 32. The shutter 32 tends to roll on the ground, but cannot overrun container 25 as the edge 33a of the shutter will engage the material edge 29. Immediately after the shutter 32 is released, the arm 53 is moved forward to position rocker 46 as shown in Fig. 4, thereby releasing the container 25 for revolution so that the container and shutter are revolved as a unit.

The load having been transported to dumping location, the arm 53 is pulled further forward to the position shown in Fig. 5. Abutment 62 will pass through the gap 35a in rail 35 and be dis-

posed for engagement by projection 65 on latch 63 arresting revolution of the shutter 32. Projection 65 also will swing latch 63 to release hook 67 from block 73 and release the container 25 which will revolve until arrested by block 36 engaging arm 38; so that the container 25 is open with material edge 29 in dumping position.

The next event is skidding beginning another cycle. Arm 51 is pulled to restore the parts of the catch and latch mechanisms to that shown in Figs. 1 and 1-A. Plate 59 will be rocked back to a position such that abutment 61 will engage latch 63, while arm 38 will be swung to engage step 37b of block 37.

Referring particularly to Figs. 8 to 15 inclusive, a frame is indicated by 76. This frame is like that shown in Figs. 1 to 7 and has a draw bar 77. A container 78 of like structure to that of the embodiment shown in Figs. 1 to 7 has a material receiving plate 79 bordering an opening for material. Secured to the side walls of container 78 are trunnion blocks 80 best shown in Fig. 10. The trunnions 81 of blocks 80 are journaled in the side bars of frame 76. Journaled on trunnions 81 is a shutter 82. Secured to a frame 83 within the container 78 and midway between its ends is an oscillating motor.

The motor 75 comprises a cylinder 84 having fixed abutments 85a and 85b diametrically opposite one another and of sectoral form with a common center concentric with the bore of cylinder 84. Concentrically disposed within the cylinder 84 is a shaft 86 having vanes 87 to sweep the spaces between abutments 85a and 85b. Trunnions 81 are hollow as shown in Fig. 10 and have hollow enlargements to which piping 88 and 89 are connected. Piping 89 is connected to a duct 89a extending around the cylinder between abutments 85a and 85b. A port 89b in abutment 85a communicates with the duct 89a and the bore 115 of the cylinder. A port 89c in abutment 85b communicates with the bore. Piping 88 communicates with a duct 88a having communicating ports 88b and 88c. The motor just described is an oscillating motor. When fluid pressure is admitted to piping 88, and the piping 89 is connected to exhaust, the impeller 86, 87 will be rocked clockwise. By arresting the flow of fluid the impeller may be fluid locked in its arrested position. By reversing the flow of fluid the impeller may be turned in the opposite direction. Secured to shaft 86 is an arm 90 having its other end secured to shutter 82. Piping 91 is secured to the frame 76 and has an end 91a rotatably secured in block 80 and suitably packed. Piping 130 is connected to piping 89 in a similar manner. Piping 91 and 92 is extended along draw bar 77 and may be connected by suitable hose to a controllable source of fluid pressure on the tractor.

It is obvious that by controlling the flow of fluid to the motor, the angular position of the shutter 82 with respect to the container 78 may be changed and the shutter may be closed or opened with the material receiving edge 79 in various selected positions.

A lug 93 is secured to shutter 82. An abutment arm 94 is pivoted to a bearing block 95 on the frame 76. It has a roller to engage lug 93. Pivotally secured to arm 94 is a link 96. A lever arm 97 is pivotally secured to the other end of link 96. Arm 97 is pivotally mounted on a pair of bearing plates 98. A double lever arm 99 is pivotally secured at one end to a bearing plate 100. Pivotally secured to arm 99 is a link 101 which is attached at its other end to rocker arm 150.

94. Forward movement of lever arm 99 will swing rocker 94 forwardly and forward movement of lever arm 97 will swing rocker 94 backwardly. Thus, rocker arm 94 may be swung into the path of lug 93 to arrest movement of the shutter or may be swung out of its path to release lug 93.

In skidding position shown in Fig. 8, the arm 94 has been positioned to arrest revolution of the 10 shutter. The motor has been operated and fluid locked to position the material receiving edge as shown with the shutter lug 93 resting on arm 94. To change to the digging event, the motor is operated to turn the container 78 clockwise and 15 then is fluid locked in this position. Arm 94 is maintained in shutter locking position. The parts are then in the position shown in Fig. 11. The transporting position is obtained by first 20 swinging lever arm 99 forwardly to move rocker 94 out of the path of lug 93, and the motor is operated to oscillate the impeller clockwise, thereby closing the shutter 82 upon the container 78 as shown in Fig. 12. The motor is then fluid 25 locked and the shutter and container may then revolve as a drum. The next event, dumping is obtained by restoring rocker arm 94 to arresting 30 position and operating the motor to cause the impeller to move counter clockwise to the end of the impeller stroke thereby positioning the parts as shown in Fig. 13. The restoration of parts to skidding position is apparent.

What I claim is:

1. A material moving device adapted to be moved along the surface of the ground comprising a frame, a material container of drum like form provided with an axially extending opening for passage of material and a material receiving edge, and a shutter shiftable in relation to said container for selectively covering said opening to provide a closed drum or opening said container, said container being journaled on said frame to serve as a ground roller.

2. A material moving device adapted to be moved along the surface of the ground comprising a frame, a material container of drum like form provided with an axially extending opening for passage of material and a material receiving edge, a shutter on said container for selectively covering said opening to provide a closed drum or opening said container, said container being journaled on said frame to serve as a ground roller, and coupling means to secure said shutter to said drum in its open or closed position.

3. A material moving device adapted to be moved along the surface of the ground comprising a frame, a material container of drum like form provided with an axially extending opening for passage of material and a material receiving edge, a shutter on said container for selectively covering said opening to provide a closed drum or opening said container, said container being journaled on said frame to serve as a ground roller, and adjustable catch means positionable to arrest revolution of said container in a plurality of angular positions or positionable to release said container for free revolution.

4. A material moving device adapted to be moved along the surface of the ground comprising a frame, a material container of drum like form provided with an axially extending opening for passage of material and a material receiving edge, a shutter on said container for covering said opening to provide a closed drum, said container being journaled on said frame to serve as a ground roller, adjustable catch means posi-

tionable to arrest revolution of said container in a plurality of angular positions or positionable to release said container for free revolution, and locking means to secure said shutter to said drum in its closed position.

5. The combination of a traction device, a material moving device adapted to be moved along the surface of the ground comprising a frame, a material container of drum like form provided with an axially extending opening for passage of material and a material receiving edge, a shutter on said container for selectively covering said opening in said container to provide a closed drum or opening said container, said container being journaled on said frame to serve as a ground roller, and control means operable by said traction device for positioning said shutter with relation to said container.

6. A material moving device adapted to be moved along the surface of the ground comprising a frame, a material container of drum like form provided with an axially extending opening for passage of material and a material receiving edge, a shutter on said container for selectively covering said opening to provide a closed drum or opening said container, said container being journaled on said frame to serve as a ground roller, adjustable catch means positionable for engagement by said shutter to arrest revolution thereof, and automatic coupling means to couple said shutter to said container in closed position, said catch means being positionable to cause said coupling means to release.

7. A material moving device adapted to be moved along the surface of the ground comprising a frame, a material container of drum like form provided with an axially extending opening for passage of material and a material receiving edge, a cylindric shutter on said container for selectively covering said opening to provide a closed drum or opening said container, said container being journaled on said frame to serve as a ground roller, adjustable catch means positionable to be engaged by said shutter to arrest the latter against revolution or positionable to release said shutter, coupling means to automatically couple said shutter to said container in closed position, said catch means being positionable to cause said coupling means to release, adjustable latching means positionable to be engaged by said container to arrest the latter against revolution in various positions of the material receiving edge or positionable to release said container for revolution.

8. A material moving device adapted to be moved along the surface of the ground comprising a frame, a material container of drum like form provided with an axially extending opening for passage of material and a material receiving edge, a cylindric shutter on said container for selectively covering said opening to provide a closed drum or opening said container, said container being journaled on said frame to serve as a ground roller, adjustable catch means positionable to be engaged by said shutter to arrest the latter against revolution or positionable to release said shutter, coupling means to automatically couple said shutter to said container in closed position, said catch means being positionable to cause said coupling means to release, adjustable latching means positionable to be engaged by said container to arrest the latter against revolution in various positions of the material receiving edge or positionable to release said container for revolution, and control mechanism

- interengaged with said catch means and said latch means operable to coercively position both of said means in their arresting positions or to coercively position both said means in release 5 positions. 80
9. A material moving device adapted to be moved along the surface of the ground comprising a frame, a material container of drum like form provided with an axially extending opening 10 for passage of material and a material receiving edge, a cylindric shutter on said container for selectively covering said opening to provide a closed drum or opening said container, said container being journalled on said frame to serve as 15 a ground roller, said shutter being journalled on said frame coaxially with said container, a lift latch on said shutter having an abutment keeper thereon, an adjustable catch positionable to be engaged by said abutment keeper to hold the shutter against revolution or positionable to clear said abutment keeper and release said shutter, a lock keeper on said container automatically engageable by said lift latch to couple said shutter to said container in closed position, said catch 20 being positionable to be engaged by said lift latch and lift the latter to release said shutter from said container, and adjustable latching means positionable to be engaged by said container to arrest the latter against revolution in various 25 positions of the material receiving edge or positionable to release said container for revolution. 100
10. A material moving device adapted to be moved along the surface of the ground comprising a frame, a material container of drum like form 30 provided with an axially extending opening for passage of material and a material receiving edge, a cylindric shutter on said container for selectively covering said opening to provide a closed drum or opening said container, said container 35 being journalled on said frame to serve as a ground roller, said shutter being journalled on said frame coaxially with said container, adjustable catch means positionable to be engaged by said shutter to arrest revolution of the latter or 40 positionable to release said shutter, coupling means to automatically couple said shutter to said container in closed position, said catch means being positionable to cause said coupling means to release said shutter from said container, peripherally spaced keeper blocks on said container, and an adjustable container latch on said frame 45 positionable to be engaged by a selected block and to arrest revolution of said container for obtaining various positions of said material receiving edge or positionable to clear said blocks and enable revolution of said container. 110
11. A material moving device adapted to be moved along the surface of the ground comprising a frame, a material container of drum like form 50 provided with an axially extending opening for passage of material and a material receiving edge, a cylindric shutter on said container for selectively covering said opening to provide a closed drum or opening said container, said container 55 being journalled on said frame to serve as a ground roller, said shutter being journalled on said frame coaxially with said container, a lift latch on said shutter having an abutment keeper thereon, an adjustable catch positionable to be engaged by said abutment keeper to hold the shutter against revolution or positionable to clear said abutment keeper and release said shutter, a lock keeper on said container automatically engageable by said lift latch to couple said shutter to said container in closed position, said catch being positionable to be engaged by said lift latch and lift the latter to release said shutter from said container, peripherally spaced keeper blocks on said container, an adjustable container latch on said frame 60 positionable to be engaged by a selected block and to arrest revolution of said container for obtaining various positions of said material receiving edge and enable revolution of said container, and control mechanism interengaged between said latches operable to coercively position both said latches in their arresting positions or to coercively position said latches in their release positions. 120
12. A material moving device adapted to be moved along the surface of the ground comprising a frame, a material container of drum like form provided with an axially extending opening for passage of material and a material receiving edge, a cylindric shutter on said container for selectively covering said opening to provide a closed drum or opening said container, said container being journalled on said frame to serve as a ground roller, said shutter being journalled on said frame coaxially with said container, a lift latch on said shutter having an abutment keeper thereon, an adjustable catch positionable to be engaged by said abutment keeper to hold the shutter against revolution or positionable to clear said abutment keeper and release said shutter, a lock keeper on said container automatically engageable by said lift latch to couple said shutter to said container in closed position, said catch being positionable to be engaged by said lift latch and lift the latter to release said shutter from said container, peripherally spaced keeper blocks on said container, an adjustable container latch on said frame 65 positionable to be engaged by a selected block and to arrest revolution of said container for obtaining various positions of said material receiving edge and enable revolution of said container, and control mechanism interengaged between said latches operable to coercively position both said latches in their arresting positions or to coercively position said latches in their release positions. 130
13. A material moving device adapted to be moved along the surface of the ground comprising a frame, a material container of drum like form provided with an axially extending opening for passage of material and a material receiving edge, a cylindric shutter on said container for selectively covering said opening to provide a closed drum or opening said container, said container being journalled on said frame to serve as a ground roller, said shutter being journalled on said frame coaxially with said container, a lift latch on said shutter having an abutment keeper thereon, an adjustable catch positionable to be engaged by said abutment keeper to hold the shutter against revolution or positionable to clear said abutment keeper and release said shutter, a lock keeper on said container automatically engageable by said lift latch to couple said shutter to said container in closed position, said catch being positionable to be engaged by said lift latch and lift the latter to release said shutter from said container, peripherally spaced keeper blocks on said container, an adjustable container latch on said frame 70 positionable to be engaged by a selected block and to arrest revolution of said container for obtaining various positions of said material receiving edge and enable revolution of said container, and control mechanism interengaged between said latches operable to coercively position both said latches in their arresting positions or to coercively position said latches in their release positions. 140
14. A material moving device adapted to be moved along the surface of the ground comprising a frame, a material container of drum like form provided with an axially extending opening for passage of material and a material receiving edge, a cylindric shutter on said container for selectively covering said opening to provide a closed drum or opening said container, said container being journalled on said frame to serve as a ground roller, said shutter being journalled on said frame coaxially with said container, a lift latch on said shutter having an abutment keeper thereon, an adjustable catch positionable to be engaged by said abutment keeper to hold the shutter against revolution or positionable to clear said abutment keeper and release said shutter, a lock keeper on said container automatically engageable by said lift latch to couple said shutter to said container in closed position, said catch being positionable to be engaged by said lift latch and lift the latter to release said shutter from said container, peripherally spaced keeper blocks on said container, an adjustable container latch on said frame 75 positionable to be engaged by a selected block and to arrest revolution of said container for obtaining various positions of said material receiving edge and enable revolution of said container, and control mechanism interengaged between said latches operable to coercively position both said latches in their arresting positions or to coercively position said latches in their release positions. 150

opening for passage of material and a material receiving edge, a cylindric shutter shiftable on said container for selectively covering said opening to provide a closed drum or opening said container, said container being journalled on said frame to serve as a ground roller, manually operable means to hold the shutter against revolution with relation to said frame or to release said shutter for revolution, and hydraulic motor means interposed between said container and shutter to adjustably couple the container and shutter in selected open positions and in closed position.

15. A material moving device adapted to be moved along the surface of the ground comprising a frame, a material container of drum like form provided with an axially extending opening for passage of material and a material receiving edge, a cylindric shutter shiftable on said container for selectively covering said opening to provide a closed drum or opening said container, said container being journalled on said frame to serve as a ground roller, an adjustable catch positionable to be engaged by said shutter to hold the latter against revolution or positionable to clear said shutter and release said latter, and

hydraulic motor means interposed between said container and shutter to adjustably couple the container and shutter in selected open positions and in closed position.

16. A material moving device adapted to be moved along the surface of the ground comprising a frame, a material container of drum like form provided with an axially extending opening for passage of material and a material receiving edge, a cylindric shutter shiftable on said container for selectively covering said opening to provide a closed drum or opening said container, said container being journalled on said frame to serve as a ground roller, said shutter being journalled on said frame coaxially with said container, an adjustable catch positionable to be engaged by said shutter to hold the shutter against revolution or positionable to clear said shutter and release the latter; an oscillating hydraulic motor having a cylinder fixed to said container, an impeller, and an arm secured to said impeller to be rocked thereby, said arm being secured to said shutter to control shifting of the latter.
